TION OF NEW YORK.

GLASSWARE-EJECTING MECHANISM.

1,406,045.

Specification of Letters Patent.

Patented Feb. 7, 1922.

Application filed March 29, 1917. Serial No. 158,242.

To all whom it may concern:

Be it known that we, EDWARD H. LORENZ and KARL E. PEILER, citizens of the United States, residing at Hartford, in the county 5 of Hartford and State of Connecticut, have invented new and useful Improvements in Glassware-Ejecting Mechanisms, of which the following is a specification.

This invention relates to the means employed for ejecting articles of glass from the molds in which they have been shaped.

The object of the invention is to produce an automatically operating mechanism which will release, eject and deliver glass articles from the walls of molds which are carried by the traveling table of a glass shaping machine, thereby minimizing the danger of their continued adhesion to the molds and interfering with the continuous 20 and efficient operation of the machine.

This object is attained in the machine illustrated by providing a plunger that is adapted to be brought down and pressed against the stem of the bottom valve of the successive molds as they arrive at their discharging position, and follow the travelling mold until the article is ejected therefrom; and arranging a hammer to travel with and strike the plunger one or more blows while 30 it is pressing against the valve stem, so that the article which has been shaped in the mold will be subjected to pressure and percussion as well as gravity for loosening it from the walls of the mold. Means are also 35 provided for engaging the article being ejected from the mold in such manner as to push it sidewise or slightly tip it and thus release it from the bottom valve should it tend to adhere thereto. These mechanisms 40 are designed to operate in consonance with the movements of the mold carrying table so that there will be no interference with the normal action of the machine.

Of the accompanying drawings Fig. 1 45 shows a front elevation of a glass pressing machine to which the present invention is applied, the lower part of the machine in this view being cut away on plane indicated by the dotted line 1—1 on Fig. 3. Fig. 2 is 50 a central vertical section of the machine on the plane indicated by the dotted line 2—2 on Fig. 1, looking in the direction indicated by the arrows. Fig. 3 shows a plan of the press-ejecting mechanism with parts of the press-

ing machine cut in section. Fig. 4 shows a 55 plan looking down from the plane 4—4 on Fig. 2, of the ratchet which causes the hammer to tap the bottom valve of the mold for the purpose of loosening the shaped article from the mold if it should tend to 60 stick therein. Fig. 5 shows a plan looking down from dotted line 5—5 on Fig. 2, of the finger which is arranged to engage with a side of the shaped article so as to move it sidewise or to tip it and release it from the 65 bottom valve of the mold should it adhere thereto.

In the machine illustrated the mold table 1 is rotatable and carries on its upper face a number of sets of molds 2 and 3. One 70 mold of each set opens upwardly and the other opens downwardly and the frame 4 which carries each set has trunnions 5 that turn in bearing blocks 6. For inverting the molds a pinion 7 is connected with one 75 trunnion and engaging with this pinion is a segmental rack 8 on an arm 9 which is connected with an arm 10 that has a segmental rack 11. This latter rack meshes with a straight rack 12 which has a roll 13 80 engaging with a cam 14. The cam is so timed that at the proper moment through the racks and pinions the positions of the molds are reversed, that is, the upwardly opening mold after having a piece of glass- 85 ware pressed therein, is turned over so as to open downward and the downwardly opening emptied mold is turned over so as to open upward for receiving its next charge of glass. 90

Each mold frame carries a vertically extending shaft 15 with an arm 16 bearing a roll 17 at its upper end and an arm 18 bearing a roll 19 at its lower end. Fastened to the upper end of each shaft is a finger 20 95 and fastened to the lower end of each shaft is a finger 21. At the proper time during the travel of the mold table the rolls engage with a fixed cam in such manner as to rotate the shaft and turn the finger at the bottom 100 from under a mold and turn the finger at the top over a mold for holding the article pressed therein while the molds are being reversed.

Under each mold carrying frame is a 105 shaft 23 which is supported so that it may be moved up and down in the lower part of the rotatable mold table. On the upper

end of this shaft and extending under the downwardly opening mold is a receiving platform 24 and at the lower end of the shaft is a roll 25 that travels in a fixed cam 5 groove 26. This cam groove is so cut that the platform is raised up beneath the downwardly opening mold to receive the article ejected therefrom; in the case illustrated the jar 27 is lowered so that the article can 10 be removed from the machine.

In each mold is a bottom valve 29 having a stem 30. This bottom valve is pushed downward at the proper time, after the glass has sufficiently cooled to permit ejection, to free the article from the walls of 15 the mold and set it on the platform.

Around the lower part of the rotatable mold carrying table is an annular gear 31. Meshing with this gear is a gear 32 fastened 20 to which is a gear 33 that engages with a gear 34 which is in mesh with a gear 35. The gear 35 is fastened on the hub of a cam 36 which is keyed to a vertical shaft 37. This shaft is supported by the frame so that 25 it can be moved vertically and also rotated. The gearing in the machine illustrated is so proportioned that the shaft turns at such speed that it makes one revolution for each mold that is brought into delivering position. The cam 36 travels on a roller 38 mounted on a stud 39 which is held in an adjustable block 40, and the shaft is pressed downward so that the cam rests on this roller by a spring 41 which is coiled about 35 it. Fastened to the upper end of the shaft 37 is a head 42, carrying a plunger 43, which is pressed downwardly by a spring 44. The head also carries an angular hammer lever 45 pivoted at 45^a to the head, and revolving 40 therewith, and having a hammer head 50 which is disposed above the upper end of the plunger 43, and is drawn downwardly by a spring 51, this hammer lever being provided with a stop abutment 60 resting 45 upon the head 42 to limit the downward movement of the hammer. A downwardly projecting arm 52 of the revolving hammer is arranged to engage with the stationary teeth 53 cut into or carried by an adjustable 50 arm 54 which in turn is fastened to the frame or other stationary part of the machine. The arm 54 is preferably made adjustable upon its support, to swing around the axis of the shaft 37, thereby enabling 55 the time of the hammering operation to be regulated. The arm 54 is secured in its adjusted positions by the bolt 54^a.

In operation, the head 42 revolves, carrying the hammer and the cushioned plunger 60 43, so as to carry the plunger in engaging coincidence with the valve stems 30 at and adjacent to the position where the paths of the revolving plunger 43 and the revolving valve stems 30 intersect or cross each other. 65 The revolving cam 36 holds the shaft, with

its head 42 and plunger 43, above the plane of the mold structures, until the plunger and the respective plunger stems are in engaging coincidence, at which time the stem 36 allows the rotating shaft and its head to 70 drop, so that the plunger 43 will exert a cushioned and increasing pressure upon the upper end of the valve stem 30. The pressure of the spring 44 will ordinarily be sufficient to release and eject the piece of 75 glassware, unless the latter adheres to its mold, in which case the plunger 43 will be pushed upwardly against the pressure of its spring 44, within the range of movement 80 of the hammer head 50, which at that time 85 is being vibrated by the teeth or notches 53 engaging the arm 52 of the hammer. Thus, if the article is not freely dislodged by the cushioned pressing movement, the percussive blows of the hammer upon the plunger 85 43 will insure the releasing and ejecting of the article, which when released drops upon the platform 24, which at that time has been brought up in position to receive it. The platform is then lowered until the 90 glassware is clear of the mold, or to any desired level at which the ware is transferred from the platform to any suitable receiver or conveyor that may be employed for transferring the finished articles of glass- 95 ware to the annealing lehrs.

To break the possible continuing adhesion of the bottom of the glass article to the face of the mold valve, when the valve is pushed or hammered down, a more or less elastic 100 finger 56 fastened to a collar 57 by a screw 58 to the frame, is arranged to project slightly into the path of the lower edge of the article as it moves along and so push it sidewise or slightly tip it. This separates 105 the bottom of the article from the mold valve if it should adhere thereto.

This ejecting mechanism may be used with a pressing machine having a continuously rotated or intermittently rotated mold 110 table carrying any desired number of molds. In the latter case the ejector may perform its functions between the intermissions of the table rotation, while the molds are moving from one station to another. 115

The invention claimed is:

1. In a glass shaping machine having a plurality of traveling molds with bottom valves, ware ejecting means including a reciprocatory plunger, and mechanism 120 adapted to force the plunger against the bottom valve of each mold in succession and thereby eject the contents of the molds while traveling.

2. In a glass shaping machine having a 125 plurality of traveling molds with bottom valves, ware ejecting means including a revolvable and reciprocatory plunger, and mechanism adapted to revolve the plunger into and out of engaging relation to the 130

successive molds and force it against the bottom valve of each mold in succession and thereby eject the contents of the molds while traveling.

5 3. In a glass shaping machine having continuously traveling molds with bottom valves, ware ejecting means adapted to contact with the bottom valve of each of said molds including a reciprocatory plunger, 10 and mechanism adapted to force the plunger against the bottom valve of each mold in succession and thereby eject the contents of the molds.

4. In a glass shaping machine having continuously traveling molds with bottom valves, ware ejecting means including a revolvable and reciprocatory plunger, and mechanism adapted to revolve the plunger into and out of engaging relation to the 20 successive molds and force it against the bottom valve of each mold in succession and thereby eject the contents of the molds.

5. In a machine for shaping glass the combination with a mold having a bottom valve, 25 of a reciprocatory plunger, mechanism adapted to force the plunger against said bottom valve, a vibratory hammer, and mechanism adapted to strike the hammer against the plunger.

30 6. In a machine for shaping glass the combination with a traveling mold having a bottom valve, of a revolvable and reciprocatory plunger, mechanism adapted to revolve the plunger and force it against said 35 bottom valve, a vibratory hammer, and mechanism adapted to strike the hammer against the plunger.

7. In a machine for shaping glass the combination with a traveling mold having a bottom valve, of a revolvable and reciprocatory plunger, mechanism adapted to revolve the plunger and force it against said bottom valve, a revolvable and vibratory hammer, and mechanism adapted to revolve the hammer 45 and strike it against the plunger.

8. In a machine for shaping glass the combination with a mold having a bottom valve, of a revolvable and reciprocatory plunger, mechanism adapted to force the plunger against said bottom valve, a vibratory hammer, mechanism adapted to vibrate the hammer against the valve, and mechanism for revolving the plunger and hammer together.

9. In a machine for shaping glass the combination with a traveling mold having a bottom valve, of a reciprocatory plunger, mechanism adapted to force the plunger against said bottom valve and thereby eject the contents of the mold, and a finger arranged to press the contents of the mold sideways as it is ejected.

10. In a machine for shaping glass the combination with a traveling mold having a bottom valve, of a reciprocatory plunger, mechanism adapted to force the plunger

against said bottom valve, a vibratory hammer, mechanism adapted to strike the hammer against the plunger, and a pushing finger arranged below the mold and arranged to push sidewise the contents ejected 70 from the mold by the action of the plunger and hammer.

11. In a device of the character described, the combination of means for applying pressure to an article in a mold to eject the same, 75 and automatically actuated means for applying an increase of pressure when said first named pressure fails to eject said article.

12. In combination, a traveling support having a plurality of molds thereon, a movable ejecting means adjacent said support and adapted to eject the contents of said molds, and means actuated in a predetermined order and time for causing the ejecting means to traverse the path of said molds 80 for said ejection, and at other times to be moved out of said path and away from said molds.

13. In a machine for shaping glass the combination with a traveling mold having a 90 bottom valve, of a rotatory and reciprocatory shaft, a spring pressed plunger and a hammer carried by the shaft, and means adapted to vibrate the hammer against the plunger and simultaneously force the plunger against 95 the bottom valve.

14. In a glass shaping machine having a plurality of molds with bottom valves, ware ejecting means adapted to apply percussion to each of the valves in succession, and 100 means for successively maintaining registration between each valve and said ware ejecting means.

15. In a glass shaping machine having a plurality of molds with bottom valves, a 105 single reciprocatory element adapted to apply successive percussions to each of the valves in succession and thereby eject the contents of the molds.

16. In a glass shaping machine, the combination with a mold having a bottom valve, of ware ejecting mechanism including a hammer adapted to deliver a succession of percussions to said valve and thereby eject the contents of the mold. 110

17. In a glass shaping machine, the combination with a mold having a bottom valve, of a reciprocatory plunger, means adapted to force the plunger against said bottom valve and means for applying a succession 120 of percussions to said plunger and thereby ejecting the contents of the mold.

18. In combination with a traveling support having a plurality of molds thereon, a movable ejecting means adjacent said support and adapted to eject the contents of said molds and means actuated in a predetermined order and time for causing the ejecting means to traverse the path of said molds and travel in substantial alignment 125 130

therewith for said ejection, and at other times to be moved out of said path and away from said mold.

19. In a glass shaping machine, the combination of a traveling support having a plurality of molds thereon and a traveling ejecting means adapted at times to coact with the said molds and at other times to move away therefrom, means for moving 10 said support and ejecting means in timed relation and means for operating said ejecting means when over said mold and in substantial alignment therewith.

20. In glass shaping means, a combination 15 of a plurality of molds traveling about a common axis, an arm traveling about a different axis, means for moving said molds and said arm whereby at times they are in

substantial alignment with each other, a plunger carried by said arm and automatic 20 means for operating said plunger when said arm is in substantial alignment with said molds, to eject the contents thereof.

21. In a glass shaping machine, the combination of a plurality of molds traveling 25 about a common axis, an arm traveling about a different axis, means for moving said molds and said arm whereby at times they are in substantial alignment with each other, a plunger carried by said arm, and means for 30 raising and lowering said plunger when it is in substantial alignment with said molds.

Signed at Hartford, Connecticut, this 27th day of March 1917.

EDWARD H. LORENZ.
KARL E. PEILER.
